UNITED STATES PATENT OFFICE.

HARRY M. TARRAS, OF TORONTO, ONTARIO, CANADA, ASSIGNEE OF ONE-HALF TO
ROBERT JOHN GASKIN, OF TORONTO, CANADA.

REFRIGERATOR.

1,337,625.

Specification of Letters Patent. Patented Apr. 20, 1920.

Application filed June 27, 1919. Serial No. 307,185.

To all whom it may concern:

Be it known that I, HARRY M. TARRAS, a subject of the King of Great Britain, residing at Toronto, in the Province of Ontario and 5 Dominion of Canada, have invented certain new and useful Improvements in Refrigerators, of which the following is a specification.

This invention relates to refrigerators, 10 and particularly to iceless refrigerators which are rendered cool by evaporation of water.

The object of the invention is to so construct a refrigerator of this character that 15 after its initial cost there is no expense incidental to its operation.

Another object is to provide a device of 20 this character in the form of a cabinet having a maximum surface exposed to evaporation thereby insuring a maximum cooling effect in the cabinet.

With the foregoing and other objects in view, which will appear as the description proceeds, the invention resides in the combination and arrangement of parts and in the 25 details of construction hereinafter described and claimed, it being understood that changes in the precise embodiment of the invention herein disclosed may be made 30 within the scope of what is claimed without departing from the spirit of the invention.

In the accompanying drawings:—

Figure 1 represents a perspective view of 35 a refrigerator constructed in accordance with this invention, with the door shown open and the food supporting shelf removed,

Fig. 2 is a transverse vertical section taken on the line 2—2 of Fig. 1,

Fig. 3 is a perspective view of another 40 form of the invention,

Fig. 4 is a central transverse section thereof,

Fig. 5 is an enlarged detail sectional view 45 taken on line 5—5 of Fig. 4, and

Fig. 6 is an enlarged detail sectional view through the lower portion of the door and the tank below it.

In the embodiment illustrated in Figs. 1 50 and 2, the refrigerator constituting this invention is constructed in the form of a cabinet 1 composed of galvanized iron or other suitable material, and preferably made airtight throughout, except at its bottom, 55 which is open over its entire area. This

cabinet is supported on suitable legs 2 of a height sufficient to space the bottom of the cabinet from the ground a suitable distance to permit air to pass freely under the cabinet and up through the open bottom thereof. 60 The opening in the bottom is preferably covered by a foraminous plate 3 composed of any suitable material, preferably of screen wire and which is slidable in and out for cleaning and other purposes. 65

Arranged around the side walls and back of the cabinet are water tanks 4 which extend up any desired height, being here shown about one-third of the height of the cabinet, although obviously their size may 70 be varied. The front walls of these tanks 4 have their upper edges grooved as shown at 5 to form seats for shelves, not shown, designed to support food and other articles to be placed in the refrigerator. These upper 75 edges are spaced from the walls of the casing 1 a sufficient distance to permit the free passage between them and the casing of the absorbent lining 10 presently to be described. 80

The tanks are equipped with a water inlet in the form of a funnel 6 which projects through one side wall thereof and at their bottom have an outlet 7 provided with a 85 controlling valve 8.

Handles 9 are shown arranged at opposite sides of the casing 1 for lifting the refrigerator from place to place.

Arranged within the casing 1 is a lining 10 composed of any suitable bibulous or 90 absorbent material, preferably heavy cotton wick loosely woven which is suspended from the center rod 11 equipped with radiating pins 12 adapted to penetrate the lining to hold it in adjusted position. This 95 center rod 11 is mounted in the front and rear walls of the casing at the top thereof and side rods 13 are arranged at the upper part of the casing adjacent these side walls as shown clearly in Fig. 2 so that the lining 10 will be held in proper vertical relation to said side walls, the ends of said lining passing down between the lips or edges 5 of the tanks and the walls of the casing 1 into the tanks 4 where they are thoroughly 105 saturated with the water contained in the tanks and the water passes up over the lining by capillary attraction. This rod 11 is provided at its front end with a handle 14 whereby it may be rotated after adjust- 110

ing the lining 10 to position it properly in relation to the tanks and to vary the area presented for evaporation.

Another lining 15 of similar material is arranged at the back of the casing and supported on a rod 16 mounted in the top thereof, the lower end of said lining dipping into the tank at the back of the casing in the same manner just above described relatively to the lining 10.

A door 17 is hinged to one side of the casing and closes the entire front thereof, being provided at its lower end with a tank 4^a similar to the tanks 4, the upper edge of which is provided with a grooved edge to form a shelf seat and which is spaced from the door to permit the lower end of a lining 18 carried by the door to dip into said tank. This lining 18 is mounted on a rod 19 supported at the upper end of door 17 on its inner face as is shown clearly in Fig. 1. A handle 20 is carried by the door and is preferably made in the form of a latch adapted to engage a catch 21 secured to the casing at one side of the door opening as is shown clearly in Fig. 1 and as is usual in apparatus of this character.

From the above description it will be obvious that the casing 1 which embodies one form of the invention is air-tight throughout, except at the bottom, which is open and screened to permit air to enter throughout and to contact with the saturated linings 10, 15 and 18, thereby causing evaporation and producing a maximum cooling effect within the cabinet so that a low temperature will be maintained therein and render the cabinet efficacious as a refrigerator.

A water gage 6' is preferably provided on the tank as shown for showing the depth of water in the tank.

In the embodiment illustrated in Figs. 3 to 6, a cabinet 21 is shown, similar to the cabinet 1 shown in the other figures, except that the water tank 24 extends entirely around the lower portion of the cabinet and the door 27 thereof at the front of the cabinet is hinged to the upper edge of the tank to open downwardly as is shown clearly in Fig. 3. This cabinet 21 is supported on suitable legs 22 of a height sufficient to space the bottom of the cabinet from the ground a suitable distance to permit air to pass freely under the cabinet and a plate 23 is mounted on said legs at a point spaced below the bottom of the tank 24. A foraminous covering, preferably of screen wire 25 spans the space between the lower edge of the tank 24 and the plate 23 so as to exclude dust, insects and the like from the interior of the refrigerator, and yet permit the free passage of air thereto.

The tank 24 has the usual filling spout 26, water gage 26', and drain cock 28, and the

cabinet is equipped at opposite sides with handles as 29 to facilitate lifting thereof when it is desired to change its location.

The inner wall of the tank 24 is grooved as shown at 24^a similar to the tank 4 of the other figures to form seats for shelves, not shown, the tank being open at its upper end inside the refrigerator for the passage into the tank of the linings or moisture absorbing elements to be described.

The absorbent linings used in connection with this refrigerator are here shown in the form of endless aprons, one of which is mounted on the door 27 and numbered 31 and passes over rollers 30 and 32 carried respectively by the door 27 and the front wall of the tank. This apron 31 is composed of any suitable absorbent material, preferably heavy cotton wick, loosely woven. The roller 32 is journaled in longitudinally extending slots 33 or brackets 34 carried by the front wall of the tank as is shown clearly in Fig. 6 so that ample space will be provided for the opening of the door 27, it being understood that the journals of the roller ride up in the slot when the door is opened and under the weight of the roller drop down when the door is closed.

A pair of parallel rollers 35 and 36 extend from the front to the rear of the top of cabinet 21, being arranged one above the other with their ends journaled in the front and rear walls of the cabinet. These rollers have fixed thereto intermeshing cog wheels 37 and 38 and the upper roller is provided with a crank handle 39 projecting from the front wall of the cabinet as is shown clearly in Figs. 3 and 4 so that the turning of this handle will operate through the cogs to turn both rollers 35 and 36 for a purpose now to be described. An endless absorbent apron 40 or lining 41 is mounted on these rollers, the upper stretch of the apron passing over the top roller and the lower stretch between the rollers 35 and 36 so that when said rollers are rotated one stretch of the apron will move in one direction and the other in the opposite direction. This apron 41 also passes over rods as 42 mounted at opposite sides of the cabinet as is shown clearly in Figs. 3 and 4 and the opposite ends of the apron depend into the tank 24 at opposite sides of the cabinet and are engaged with rollers, not shown, similar to those over which the apron 31 passes.

The rollers 35 and 36 are provided with a plurality of radiating pins or spurs 40 which are designed to penetrate the apron and take hold thereof to insure the movement of the apron on the turning of the rollers.

An apron, 43, similar to the apron 31 is arranged at the back of the cabinet and extends over rollers 44 and 45 located respec-

tively at the top of the cabinet and the bottom of the tank at the rear thereof as is shown clearly in Fig. 4.

The door 27 is preferably provided with 5 an ordinary catch 27^a for holding it in closed position.

The operation of this cabinet is the same as that shown in Figs. 1 and 2, except that endless aprons are employed in this form of 10 the invention, instead of the single members used in the other form.

From the foregoing description, taken in connection with the accompanying drawings, the advantages of the construction and 15 of the method of operation will be readily apparent to those skilled in the art to which the invention appertains and while I have described the principle of operation of the invention together with the device which I 20 now consider to be the best embodiment thereof, I desire to have it understood that the device shown is merely illustrative and that such changes may be made as are within the scope of the claimed invention.

Having thus fully described my invention, what I claim as new and desire to 25 secure by Letters Patent, is:—

1. In an iceless refrigerator, a cabinet having a ventilating opening, a water tank 30 arranged around said cabinet, a roller extending transversely across the top of the cabinet and through one wall thereof, a handle on said end, a liquid absorbent lining suspended over said roller, said lining 35 dipping into said tank and movable by the turning of said roller to vary its position in the cabinet.

2. In an iceless refrigerator, a cabinet 40 closed air-tight except at its bottom, a water tank arranged around said bottom, a roller extending transversely across the top of said cabinet and extending through one wall thereof, a handle on said end, pins radiating from said roller, a liquid absorbent lining 45 suspended over said roller and engaged by said pins, said lining dipping into said tank and movable by the turning of said roller to vary its position in the cabinet.

3. In an iceless refrigerator, a cabinet 50 closed air-tight except at its bottom, a water tank arranged around said cabinet at its lower end and opening at its top within said cabinet, parallel rollers extending transversely across the top of the cabinet one 55 above the other and having radiating spurs, intermeshing cogs carried by said rollers, means for turning one of said rollers whereby the other is rotated, and an endless apron having the stretches thereof, one passing 60 over the top roller and the other between the rollers, and rollers in the tank at opposite sides of the cabinet around which said apron passes.

4. In an iceless refrigerator, a cabinet, a

water tank arranged around said cabinet at 65 its lower end and opening at its top within said cabinet, parallel rollers extending transversely across the top of the cabinet, intermeshing cogs carried by said rollers, means for turning one of said rollers whereby 70 the other is rotated, and bibulous material supported by said roller and movable on the turning thereof.

5. In an iceless refrigerator, a cabinet, a water tank arranged around said cabinet at 75 its lower end and opening at its top within said cabinet, said cabinet having a ventilating opening, parallel rollers extending transversely across the top of the cabinet, intermeshing cogs carried by said rollers, 80 means for turning one of said rollers, whereby the other is rotated, a bibulous material supported by said roller and movable on the turning thereof, and rollers in the tank at opposite sides of the cabinet with which 85 said material is engaged.

6. In an iceless refrigerator, a cabinet having a ventilating opening, a water tank arranged around said cabinet, a roller extending across the top of said cabinet, a 90 liquid absorbent lining suspended over said roller and dipping into said tank, means for turning said roller to vary the position of the lining in the cabinet, a door for said cabinet, a bibulous lining on the inner face 95 of said door, and a tank into which said lining dips.

7. In an iceless refrigerator, a cabinet having a ventilating opening, a water tank arranged around said casing, a roller extending across the top of said cabinet, a 100 liquid absorbent lining suspended over said roller and dipping into said tank, means for turning said roller to vary the position of the lining in the cabinet, a door 105 hinged to open downwardly, rollers mounted one on the door and one in the tank, and an endless apron of bibulous material passing over said rollers.

8. In an iceless refrigerator, a cabinet 110 having a ventilating opening, a water tank arranged around said casing, a roller extending across the top of said cabinet, a liquid absorbent lining suspended over said 115 roller and dipping into said tank, means for turning said roller to vary the position of the lining in the cabinet, a door hinged to open downwardly, rollers mounted one on the door and one in the tank, one of said rollers being vertically movable, and an 120 endless apron of bibulous material passing over said rollers.

In testimony whereof I affix my signature in presence of two witnesses.

HARRY M. TARRAS.
